OUTDOOR ILLUMINATED SIGN

Conrad J. Escalante, 852 E. Ocean Ave.,
Long Beach, Calif. 90802

Filed Sept. 23, 1970, Ser. No. 25,151

Term of patent 14 years

Int. Cl. D20—03

U.S. Cl. D96—12

FIG. 2.

FIG. 1.

FIG. 3.

FIG. 6.

FIG. 4.

FIG. 5.

FIG. 9.**FIG. 10.****FIG. 11.**FIG. 1 is a front elevation of an outdoor illuminated sign showing my new design, the undisclosed rear is a mirror image of the front;

FIG. 2 is a side elevation, as seen from the left of FIG. 1;

FIG. 3 is a side elevation as seen from the right of FIG. 1;

FIG. 4 is a top plan view thereof;

FIG. 5 is a bottom plan view thereof;

FIG. 6 is a front elevation of a modified embodiment of the sign illustrated in FIG. 1; the undisclosed rear side is a mirror image of the side shown, with the exception of the lettering the remaining views are similar to FIGS. 2, 3, 4 and 5;

FIG. 7 is a front elevation of a further modified embodiment of the sign illustrated in FIG. 1;

FIG. 8 is a side elevation as seen from the right of FIG. 7.

FIG. 9 is a side elevation as seen from the left of FIG. 7;

FIG. 10 is a top plan view thereof; and

FIG. 11 is a bottom plan view thereof.

I claim:

The ornamental design for an outdoor illuminated sign, substantially as shown and described.
